SLEEPING BAG

Jean Bookbinder, Philadelphia, Pa.

Application March 6, 1946, Serial No. 652,374

1 Claim. (Cl. 2—69.5)

2

1 My invention relates to wearing apparel and relates particularly to a garment to cover an infant or very young child safely and comfortably at night.

Heretofore, sleeping garments for an infant or a very young child up to three years of age have been manufactured and sold. One type of sleeping garment has been a bag-like member substantially covering the body and feet of the infant and having strings attached to the garment whereby the strings may be tied to the bed in order to prevent the average child, who squirms around, from becoming fatally entangled in the garment. Habits formed by the infant have a lasting effect, and restricting the movement of the normal infant by tying him to the bed or placing the infant within a constricting garment with a tight neck band tends to inhibit the infant's natural movements, thereby impeding the infant's natural development.

In other cases loose blankets and coverings are used for the infant and these present a danger of smothering the infant by virtue of entanglement.

The prior art sleeping coverings present problems of inhibiting the natural movement of the infant or of presenting dangers of smothering or of strangling.

It is, therefore, an object of my invention to overcome the difficulties presented by the prior art sleeping coverings.

Another object of my invention is to provide a sleeping bag for an infant which is comfortable, completely safe, and permits complete freedom of movement of the infant.

Another object of my invention is to provide a sleeping garment for an infant whereby the infant may change his position during the sleeping period as frequently as desired with freedom and safety, and the child may safely revert to sleeping on his stomach or his back as he chooses for his own comfort.

Another object of my invention is to provide a sleeping garment for an infant wherein no surplus folds endanger the child, the garment does not ride-up on the infant, and wherein the child may play freely, completely uninhibited, and stand, sit, walk, or crawl in it.

Other objects of my invention are to provide an improved device of the character described, that is easily and economically produced, which is sturdily constructed, and which is highly efficient in use.

With the above and related objects in view, my invention consists in the details of construc-

tion and combination of parts, as will be more fully understood from the following description, when read in conjunction with the accompanying drawing in which:

5 Fig. 1 is a front view of an infant's sleeping garment embodying my invention.

Fig. 2 is a rear or back view of the infant's sleeping garment.

Fig. 3 is a pattern of the sleeping garment cut 10 in one piece.

Fig. 4 is a view of a sleeping garment illustrating an infant enveloped by the garment.

Referring now in detail to the drawing wherein similar reference characters refer to similar parts, I show a sleeping garment for an infant or young child up to three years of age whereby the infant or child may be covered safely and comfortably at night. The garment may be easily washed, it presents no troublesome and dangerous ties, no loose ends, and the infant may be placed within the garment in a few seconds. The child also may play freely, completely uninhibited, and stand, sit, walk, or crawl in the garment.

25 A single piece of material or panel 10, such as all wool blanketing for winter, or cotton blanketing for spring and summer, may be used as the pattern. The pattern preferably is made of parallel side edges 12, 14 and a bottom edge 15

30 substantially at right angles to the side edges. The upper edge has a configuration cut therein to serve as armholes 16, 18 and a neck opening 20. Starting from the center of the material 10, along the upper edge, is an arcuate neck

35 opening outline 22 which is almost semi-circular. Proceeding to one side is an inclined edge 24 which is inclined downwardly to form a portion of a front shoulder. The edge 24 terminates in a sharp V-shaped notch 26 which serves

40 to sever the material for an armhole; from the other side of the V-shaped notch is the back shoulder portion 24A which coincides with shoulder portion 24, and a portion of the rear neck portion 22A terminates in the back shoulder portion 24A.

The other side is symmetrically arranged to form sloping shoulder portions 28, 28A, a second deep V-shaped notch 30, and a neck portion 22B.

50 The distance of approximately one-half the width of the panel between the notches 26, 30 represents the front of the garment, and the distance of approximately one-quarter the width of the panel from the notches to the side edges

55 12, 14 represents the back of the garment. The

panel 10 thereby is divided into a central section and side sections. The edges 12, 14 may be brought together by a series of buttons 32 and complementary buttonholes 32A, or zippers (not shown).

The bottom edge is closed by a series of stitches 34 and the side edges 12, 14 closed by a series of stitches 35 to a point close to the bottom.

The two shoulders are closed by a series of stitches 36, 36A, and the neck opening and the arm openings may be faced with rayon or other suitable material 38 which eliminates the coarse edges, adds comfort to the wearer, since rayon is non-irritating to tender skin, and also is attractive in appearance.

In use, an infant is slipped into the bag and the buttons pulled through the buttonholes, the two side edges being overlapped by about three inches and also being trimmed with rayon or other suitable material.

The cut and depth of the shoulder eliminates the necessity of sleeves, since it extends to approximately the elbow of the child and affords more freedom of the arms than sleeves.

The sleeping garment may be worn over the child's pajamas or nightgown, it is inexpensive, and because of the simplicity of the construction is easily assembled, and it is made in sizes according to the age of the child.

Although my invention has been described in considerable detail, such description is intended as being illustrative rather than limiting, since the invention may be variously embodied, and the scope of the invention is to be determined as claimed.

I claim as my invention:

A sleeping garment for infants comprising a single panel having substantially parallel side edges, a bottom edge at right angles to said side edges, a pair of narrow-in-width deep V-shaped notches being formed in said panel and extending downwardly from the upper edge and spaced from the side edges approximately one-quarter of the width of said panel and defining a central section and side sections, a portion of the top edge 10 adjacent each notch sloping upwardly and outwardly therefrom to form shoulder portions, the inner ends of the centrally disposed sloping edges being connected by a downwardly disposed arcuate edge, the ends of the outwardly disposed sloping edges being connected to the outer side edges of the panel by arcuate edges, the side sections being folded upon the central section and disposing the said side edges of the panel adjacent one another, the registering bottom edges being 15 connected to form a closed bottom, the said registering sloping edges being secured together to form shoulder portions, the registering arcuate edges forming a neck opening, and means to releasably hold said longitudinal edges together 20 for substantially the full length of the garment.

JEAN BOOKBINDER.
